UNITED STATES PATENT OFFICE.

WALTER HAYES FITCH, OF INDIANAPOLIS, INDIANA.

RAIL-JOINT.

SPECIFICATION forming part of Letters Patent No. 558,272, dated April 14, 1896.

Application filed September 7, 1895. Serial No. 561,734. (No model.)

To all whom it may concern:

Be it known that I, WALTER HAYES FITCH, a citizen of the United States, residing at Indianapolis, in the county of Marion and State 5 of Indiana, have invented certain new and useful Improvements in Rail-Joints; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to a new and novel method of strengthening the joints or rail-splices of railroads to afford a reliable means whereby the joint or splice is supported and rendered as strong and stiff as any other part 20 of a rail; and it consists of truss-rods of peculiar form in connection with either a common form or special design of fish-bar splice and the usual cross-ties, as will be more fully described hereinafter.

25 In the present state of the art it has been found impossible in the operation of railroads to prevent low joints, or an injurious depression of the line at each splice of the rails, which are in sections of suitable length for 30 convenient use. At each joint a small space is left between the ends of the two adjoining rails to permit expansion longitudinally. When the wheels of cars roll along the rails and over these spaces, they produce a pounding effect upon the rail ends, gradually flattening the tops of the rails at these points, doing irreparable damage to the rails, the life of which is greatly lessened on that account, besides much damage is done also to rolling 35 equipment on account of the incessant jarring. My objects are to obviate these objections and to provide a rail-joint that is readily adjustable vertically to maintain an even surface on top; to provide for a distribution 40 of the load or unequal effect of the load at joint due to the wheels passing across the expansion-space from one rail to another, so that the ties on either side of a joint-tie will receive a part of the joint-strains; to prevent 45 the slight alternating vertical motion of the ends of rails at joints, which otherwise assist in the flattening of the tops of rails at

the ends, and to so secure the rails at the joints that on curves, should the spikes become loose, as they commonly do, the rail cannot turn over under the usual conditions in service.

55 My invention is of few parts, simple in design, easily and cheaply constructed, economical and durable in use, and its merits 60 will be obvious by an examination of the description of details and accompanying drawings, in which—

Figure 1 represents a side view of a portion of two rails joined by my device. Fig. 2 is a 65 cross-sectional view of a rail and splice-bars on line A B of Fig. 1, showing ends of truss-rods. Fig. 3 is a side view of an end portion of a splice-bar, showing a modified truss-rod having its end lugged over the end of splice-bar; and Fig. 4 is a plan view of same.

In the construction of my device I make the truss-rods G in three parts each, and when connected each end of a truss-rod has an eye 75 l, through which an ordinary track-bolt of 80 suitable length is inserted. Each rod G has a flattened portion n, which is sufficiently broad to afford a solid bearing against the under side of a joint-tie without cutting into the softer texture of wood. Between this 85 and one end of the rod it is divided into two parts h and m, each of which have screw-threads, one right and the other left pitch at their stub ends, to which is screwed a turn-buckle L for the purpose of adjustment and taking up slack when necessary. This turn-buckle may be made with threads at one end only, the other having a swivel, but I prefer both ends to be threaded. In some cases I make the truss-rods having lugged ends, 90 which relieves the securing-bolts from the shearing transverse strain, transferring it directly against the ends of the splice-bars, while the bolts secure the rod ends against the side of the splice-bar. Suitable cross-ties 95 are used in the usual manner and the rails C are laid and spiked upon them. I provide a metallic plate N on top of joint-tie approximately as long as the width of a tie and wide as the bottom of rail, or wider, when used 100 upon soft ties for the purpose of preventing the chafing of the wood by the stub ends of the rails as the wheels pass from one rail to another. These are secured to the tie by spikes.

The splice-bars D, one at each side of the rails at each joint, extend across the joint-tie H to the next ties H' and H² at either side and are bolted against the rails in the usual manner. As these splice-bars may have no horizontal angle-plates they permit of the rails at joints conforming more readily to the necessary curves of the road, while the loss of the strength of such angle-plates, if omitted, is more than compensated by my truss-rods. These have their ends secured by bolts F at the ends of the angle-bars, while the flattened centers pass under the joint-tie H. The turnbuckle being turned on a rod it becomes taut and raises the tie H and joint until the track-rails present a straight surface on top. The rods thus prevent the joints becoming low, even when a joint-tie should not be solidly resting upon the grading, as the trusses bind the rails vertically as strongly as the other parts of a rail, so that the adjacent ties H' and H² will support a joint until they should gradually settle down from neglect. This would cause a long sag only and have none of the evils of a sag of the joint-tie only, as is now common with other splices. This manner of securing the rails to the joint-ties also prevents the rails from being turned over on curves where the lateral thrust is most severe. Provision is made as usual for expansion and contraction of rails by having elongated holes in the rails, through which the splice-bolts loosely enter.

Having described my invention, what I claim as new, and desire to secure by Letters Patent, is—

1. In a railway trussed rail-joint having a pair of splice-bars bolted to the sides and securing the ends of two rails together and the usual cross-ties upon which said rails are spiked, one of said ties being under said joint, the combination of the truss-rods G having the eyes l at each end thereof attached by said splice-bolts, and the turnbuckle L attached to the parted parts h and m; the flattened portion n at middle part of said truss-rods bearing against under side of said joint-tie and the plate N spiked to said tie under said rail-joint, substantially as shown and described.
2. In a railway trussed rail-joint having splice-bars bolted to the sides of the rails connecting the ends thereof and a supporting cross-tie under said rails at joint, the com-

nation of the truss-rods G having the eyes l 55 at each end bolted by means of the said splice-bolts to the sides near the ends of said splice-bars; the flattened portion n at middle of said truss-rods bearing against under side of said cross-tie, and the turnbuckle L for producing a strain on said truss-rods, substantially as shown and described.

3. In a railway-rail joint having metallic splice-bars, suitable cross-tie under said joint and truss-rods connected at their ends to the 65 sides of said splice-bars supporting at their centers the said joint-tie, the combination with said truss-rods, of a lugged end on each extremity of said rods extending over and against the ends of said splice-bars, and a 70 hole in said lugged end through the same to receive a bolt by which it may be secured flatwise against the side of said splice-bars, substantially as shown and described.

4. In a railway-rail joint, having two rails 75 with ends adjacent, a cross-tie under said rail ends, a number of cross-ties under said rails adjacent on either side of said joint-tie, the rails being spiked to said ties, a splice-bar on each side of said rail ends bolted to sides 80 of same and extending across said joint-tie to each of the next adjoining ties, the combination of the under truss-rods G, having the eyes l and turnbuckle L bearing at their centers against under side of said joint-tie and 85 having their ends secured by joint-bolts to ends of said splice-bars so that said rods and said bars with said tie as a strut form a complete truss and bond to prevent said rails from turning over from a normal position, 90 substantially as and for the purpose shown and described.

5. In a railway-rail joint having splice-bar connections and a cross-tie under said joint, the combination of the truss-rods G having 95 the turnbuckle L and connected at the ends to the ends of said splice-bars, and the center bearing against the under side of said tie as a strut for said truss-rods, the whole securing said rails to said tie, substantially as shown 100 and described.

In testimony whereof I affix my signature in presence of two witnesses.

WALTER HAYES FITCH.
